Trustee.

UNITED STATES PATENT OFFICE.

IRVING R. ALLEN, OF WHEATON, ILLINOIS.

DISPLAY DEVICE FOR GARTERS.

Application filed May 13, 1925. Serial No. 30,034.

To all whom it may concern:

Be it known that I, IRVING R. ALLEN, a citizen of the United States, and a resident of Wheaton, Du Page County, and State of Illinois, have invented certain new and useful Improvements in Display Devices for Garters, of which the following is declared to be a full, clear, and exact description.

This invention relates to display device 10 for garters, and its principal object is to provide a simple, inexpensive, and attractive device for displaying garters in stores or wherever sold, which device also acts as a container for the garters during storage and 15 shipment. Another object is to provide a garter displaying device which shall simulate parts of a pair of legs with socks depicted thereon, and adapted to receive and support a pair of garters in a position which 20 will give the impression of supporting the socks on the leg portions of the device. Another object is to provide a cardboard displaying device shaped to simulate parts of a pair of legs and scored along a vertical 25 line midway between the side edges of the device, whereby it may be bent along said score line to form two angularly disposed halves or leg parts, that will stand upon a counter or show case with the garters there- 30 on in a position occupied when supporting the socks on the legs, the device being capable of being further folded upon said score line to bring the two halves together, whereby the device, with the garters thereon, 35 may be slipped into a bag or wrapper when sold and given to or shipped to a customer. The invention consists in the several novel features hereinafter fully set forth and claimed.

40 The invention is clearly illustrated in the accompanying drawing, in which:

Fig. 1 is a front elevation of a display device for garters illustrating a pair of garters thereon, one of which is shown in dotted 45 lines and the device being spread out flat, and Fig. 2 is a plan of the device, showing two positions thereof.

Referring to said drawing, the reference character 5 designates a cardboard piece 50 which may be blanked out from a sheet of cardboard by suitable dies. The cardboard piece 5 comprises two halves 6, 6 each shaped to simulate a part of a human leg and having printed thereon, near the lower end, a 55 design 7 simulating the upper end of one of

a pair of socks. The cardboard piece 5 is scored vertically midway between its side edges along the line 8, which line extends between the points 9, 10 and from said points 9 and 10, the cardboard piece is formed with 60 two notches 11, 12, the edges of which are curved to correspond with the opposite edges of the two halves or leg members 6, 6, to give the shape of legs to them.

Each leg member 6, 6, may be formed with 65 a slot 13, immediately above the edge of the portion that contains the printed matter 7, depicting the sock portion, and below said edge is a hole 14, the purpose of which will appear later.

The elastic band portion 15 of a garter 16 is slipped over the upper portion of each leg member 6, 6, the tab 17 is slipped back through the slot 13 and the button head 18 brought forward through the hole 14. The 75 loop 19 is then engaged with the button head 18.

The cardboard piece is folded slightly upon its score line 8 to bring the two leg members 6, 6, at a wide angle to each other, 80 whereupon the device may be set upon a flat surface such as the top of a counter, show case and the like for the purpose of displaying the garters.

When stood up the device displays the 85 garters more effectively than when displayed in a box or carton. It gives to the possible customer a more accurate impression of the garters as they appear when worn.

Another advantage of the device is that 90 it may be folded along the score line 8, to bring the two halves together, thereby reducing the size of the device and forming a holder for the garters which may be placed 95 in a small paper bag or package when sold to a customer. If desired, the upper portions of the leg members 6, 6, may be tinted to represent flesh color to make the article 100 more attractive. The back thereof furnishes space for advertising matter or other printed data. The article is simple in construction, requires but little space in use and while in storage.

More or less variation of the exact details 105 of construction is possible without departing from the spirit of this invention; I desire, therefore, not to limit myself to the exact form of the construction shown and described, but intend, in the following claim,

to point out all of the invention disclosed herein.

I claim as new, and desire to secure by Letters Patent:

5 A display device for garters, comprising a flat cardboard piece formed with a bifurcated upper portion and a bifurcated lower portion, both forming two joined similar halves shaped to simulate parts of a pair of 10 human legs, said furcations leaving V-shaped notches extending in from the upper and lower edges, and the cardboard piece being scored vertically between said notches, and the lower portions of said halves having

15 surface portions depicting parts of socks, the upper bifurcated portions being adapted to receive the elastic band portions of garters and the bottom of the upper notch acting as a stop whereby the elastic band portions of the garters may be aligned across 20 the display device, and said halves being folded upon said score line, whereby the two halves may assume a widely spreading angle to display the garters in position as worn, and whereby the two halves may be folded 25 together to partly enclose them.

IRVING R. ALLEN.
